CLAIM

The ornamental design for a resonator device as shown and described.

DESCRIPTION

FIG. 1 is a perspective view showing a resonator device as seen from the top, front, and first side;
FIG. 2 is a front elevation view thereof;
FIG. 3 is a back elevation view thereof;
FIG. 4 is a first side elevation view thereof;
FIG. 5 is a second side elevation view thereof;
FIG. 6 is a top plan view thereof; and,
FIG. 7 is a bottom plan view thereof.
The broken lines shown in the drawings represent unclaimed subject matter and form no part of the claimed design.
